AMMUNITION SHELL

George Neumann and Frank Schneider,
Milwaukee, Wis.

Application June 6, 1940, Serial No. 339,112

1 Claim. (Cl. 102—29)

Our invention refers to explosive shells, and it is particularly adapted as a defense against airplane raids.

The invention has for its primary object to provide an ammunition shell unit, which may develop a secondary explosion due to striking an airplane or other object, whereby the body of the shell will grapple or engage the object struck and simultaneously discharge a parachute, which is connected to the shell by a suitable cable, thus putting out of commission the airplane or object struck.

With the above and other minor objects in view, the invention consists in certain peculiarities of construction and arrangement of parts, as will be hereinafter fully set forth in connection with the accompanying drawing and subsequently claimed.

In the drawing:

Figure 1 represents a sectional elevation of a shell embodying my invention; and

Figure 2 illustrates a perspective view of the shell after contacting with an airplane, showing the parachute functioning to anchor or retard the plane while in midair.

Referring by characters to the drawing, the numeral 1 indicates a metallic jacket provided with a propelling explosive charge 2 at the rear end, which charge is compressed against a disc 3 that is longitudinally held against a stop 4 arranged to be otherwise movable, whereby it is discharged through the rear end of the jacket.

A piston-head 5 is loosely mounted near the front end of the jacket, and has attached thereto a coiled cable 6, which cable is also attached to the leaders 7 of a parachute 8; the same is shown being snugly folded within the shell with its crowned end abutting the disc 3.

Spaced from the piston-head 5 is a fixed disc 9, which disc carries a percussion cap 10, and between the fixed disc and piston-head is an auxiliary explosive charge 11.

A spring-controlled plunger rod 12 is reciprocatedly mounted in the nose of the shell, and has projecting from said nose a tappet finger 13. The rear end of the plunger rod carries a hammer 14, adapted to contact and explode the auxiliary charge 11. The hammer 14 is also provided with fingers 15, which engage spring-

controlled trip arms 16 and pivot grapple hooks 17, the said grapple hooks being exterior of and normally closed against the shell 1.

From the foregoing description, it will be noted that when the tappet finger 13 engages, for example, the body of an airplane, it will produce a hammer blow upon the cap of the auxiliary charge 11. This explosion of the charge will cause the piston-head to travel rearwardly in the jacket and strip the parachute and associated parts from the shell 1.

As shown in Figure 2, in the event that the shell pierces a wing of an airplane, the grapple hooks 17, being expanded or spread out due to action of the hammer blow, will contact with the surfaces of the wing, and, thus, securely lock the shell into anchor engagement with said wing. Hence, the parachute will offer a substantial resistance or anchorage element with reference to the airplane, and said plane will be twisted from its course, or checked in speed to such an extent as to put the plane out of action. It will be observed, however, that this same result with reference to the shell and associated parachute will be had in the event that the shell strikes any portion of the plane.

Furthermore, in some instances, we may utilize a time-controlled explosive element associated with the auxiliary charge, whereby the shell may be discharged and function at a pre-determined distance from its point of travel; and, consequently, when so exploded, the cable and parachute will readily entangle a moving object, such as an airplane.

While we have shown and described a shell embodying our invention minutely as to details, it is understood that we may vary the structural features of the shell indefinitely within the scope of the claim to accomplish the desired results.

We claim:

A shell comprising, a jacket, a plunger extending through the nose of the jacket, a capped explosive charge engageable with the plunger, pivoted grapple hooks having arms engageable with the plunger, a piston-head positioned rearwardly of the explosive charge, and a cable and parachute secured to the piston-head.

GEORGE NEUMANN.
FRANK SCHNEIDER,
